UNITED STATES PATENT OFFICE

JAMES H. HORSLEY, OF CHICAGO, ILLINOIS, ASSIGNOR TO UNIVERSAL LAMP COMPANY, OF CHICAGO, ILLINOIS, A CORPORATION OF ILLINOIS

ACETYLENE LAMP

Application filed February 10, 1930. Serial No. 427,154.

This invention relates to improvements in acetylene lamps, particularly the type designed for miners' use.

The general object of the invention is the provision of an improved feature of equipment for such lamps whereby manipulation of the lamp for refilling is facilitated and whereby the lamp is afforded protection against distortion and injury such as frequently results from a customary method of handling it.

Other objects will be pointed out or indicated hereinafter or will be apparent upon an understanding of the invention.

15 In the accompanying drawing I show certain forms in which the invention may be embodied and utilized, but it is to be understood that these are presented for purpose of illustration only and are not to be accorded any interpretation calculated to limit the appended claims short of the true and most comprehensive scope of the invention in the art.

In said drawing,

25 Fig. 1 is a side elevational view of a miner's acetylene lamp embodying the present invention;

Fig. 2 is a sectional elevation of the carbide reservoir or container;

30 Fig. 3 is a perspective view of the gripping buffer; and

Fig. 4 is a view illustrating a manner in which the carbide container is customarily treated incident to refilling.

35 There are various familiar forms of miners' acetylene lamps which have detachable carbide containers forming the lower portion of the lamp assembly, said containers being screw-threaded to the cooperating portion of the lamp and removable for purpose of refilling. When a lamp has been burning for some time, the carbide container is likely to become quite hot, both from the heat of the flame and from the heat of re-40 action generated by the slaking of the carbide. This not only renders it difficult to handle for unscrewing it, but also tends to make the screw-threaded portion bind, due to the expansion of the heated metal. With 45 slaking, the carbide residue becomes more or

less caked or compacted in the carbide container, and its removal in either a moistened or dry condition is thereby rendered somewhat difficult. In order to loosen the caked residue so as to permit its being shaken out 55 of the container, the miners are in the habit of tapping the container against some hard object, and as a result of such treatment the containers are frequently dented and distorted and rendered leaky by the opening of 60 a seam or perforation of the metal.

The present invention provides a simple and convenient improvement in the construction and equipment of such lamps, whereby the removal of the heated carbide container 65 is facilitated and it is protected from injury by treatment such as just described.

The nature of the improvement will be clearly ascertained from the illustrations. In the drawing the reference numeral 10 designates the body portion of a miner's lamp of well known design and construction, which body portion carries the water reservoir, water feed control, burner, reflector, etc., as well as the hook 11 and brace 12 whereby the 70 lamp is adapted to be suspended and positioned on the miner's cap. Screw-threaded into the lower portion of the body portion is the carbide container 14, which is a hollow metal receptacle adapted to hold the carbide 75 from which the gas is generated by water which is dropped into the container from the water feed device. The screw-threaded neck 14^a of the container fits in a correspondingly 80 screw-threaded socket on the body portion, and a tight joint is afforded by means of a rubber gasket 15. An outstanding peripheral bead 14^b is provided at the junction of the bottom and side of the container, said bead either being rolled in the metal, or being 85 formed by the seaming of the bottom and side together. A gripping buffer 16, formed of a suitable yielding material having heat insulating properties, such as rubber, is provided and fitted onto the lower portion of 90 the container. This gripping buffer is of cup-like form, so that it will embrace the peripheral wall of the container for some distance, and cover the edge or bead at the junction 95 of the bottom and side. It preferably is pro- 100

vided with an internal groove 16^a for receiving the bead at the bottom of the container, and should be of substantial thickness in the portions surrounding the bead. Due to its 5 elastic properties, it may be thus fitted onto the container and hold a position in close contact with the same. It should fit with sufficient closeness to prevent its rotating on the container, and such adhesion may be 10 brought about by effects occurring from the heating of the container.

This gripping buffer affords a secure engagement for the hand in the unscrewing of the container from the lamp body, and also, 15 due to its heat insulating properties, protects the hand from the heat of the container in such operation. As illustrated in Fig. 4, this equipment also affords an effective buffer to protect the container against denting and distortion when pounded upon a solid object in 20 the customary fashion for loosening the carbide residue. It also affords a heat insulating element between the carbide container and a portion of the miner's cap against 25 which it may bear when the lamp is worn on the cap.

What I claim is:

1. The combination with an acetylene lamp having a body portion and a detachable carbide container, of a gripping buffer of elastic heat-insulating material enveloping the lower portion of the carbide container and constituting a hand-hold and protection for same against impacts to dislodge carbide sludge 35 from the container.
2. A combination as specified in claim 1 and wherein the carbide container has a peripheral protuberant bead at the junction of its side and bottom portions and the gripping buffer has an internal circumferential channel 40 accommodating the bead.
3. An attachment for the carbide container of an acetylene lamp, comprising a cup-like gripping buffer formed of elastic heat-insulating material and shaped to fit onto and envelop portions of the carbide container at and adjacent the junction of the side and bottom portions of the latter to form both a protection for said portions against impacts to 45 dislodge sludge and a hand-hold for manipulation of the container.
4. An article as specified in claim 3 and wherein the gripping buffer is formed with an internal circumferential channel for accommodation of a peripheral bead on the container.

In testimony whereof I have hereunto subscribed my name.

JAMES H. HORSLEY.
